UNITED STATES PATENT OFFICE.

HERBERT W. SNYDER AND ALBERT J. TOWNSEND, OF LIMA, OHIO.

LOCOMOTIVE SADDLE STRUCTURE.

Application filed December 18, 1922. Serial No. 607,517.

To all whom it may concern:

Be it known that we, HERBERT W. SNYDER and ALBERT J. TOWNSEND, citizens of the United States, both residing at Lima, in the county of Allen and State of Ohio, United States of America, have invented certain new and useful Improvements in Locomotive Saddle Structures, of which the following is a specification.

Our invention relates to locomotive saddle structures, and is especially concerned with provisions for taking care of the exhaust steam.

Heretofore, it has been the general practice to combine the locomotive cylinder, steam chest or valve chest, saddle (or half of it), and the exhaust passages all in one single casting. This is a somewhat difficult thing to do, especially when the parts are made of cast steel; and in order to arrive at a design that can be fabricated in one casting, it is often necessary to make the size and shape of the exhaust passages quite different from what would be desirable for the best handling of the steam. Exhaust passages have to be taken off the sides of the steam chest, and must be made rectangular in cross-section, or with sharp bends,—all of which tends to restrict the flow of the exhaust steam and so impose back pressure on the engine pistons.

Through our invention, these drawbacks of present practice can be overcome: resistance to the flow of the exhaust steam can be reduced to a minimum, and the construction considerably simplified. How these and other advantages can be realized through the invention will appear from our description hereinafter of the best construction embodying it that is known to us.

In the drawings, Fig. 1 is a plan view of a locomotive saddle and associated parts conveniently embodying our invention, the right-hand half of the structure being in horizontal section as indicated by the line 1—1 in Fig. 2.

Fig. 2 is a rear end elevation, with the left-hand half of the structure in cross section.

Fig. 3 is a side elevation, with the left-hand half of the structure in longitudinal section as indicated by the line 3—3 in Fig. 2.

In the construction here illustrated, each main engine cylinder 5 and its valve chest 6 are cast in one piece with one another and with the structure of the ports 7, 7 intercon-

necting them, as well as with the corresponding lateral half 8 of the saddle,—the two saddle halves 8, 8 being flanged and bolted together at 9 in the usual way. As shown, the ports 7, 7 are almost straight and of minimum length, so that the resistance which they offer to passage of live or exhaust steam between valve chest and cylinder is minimized. The relatively thin, hollow webs 11, 11 containing the ports 7, 7 are substantially in line and directly united with the transverse webs 12, 12 that form the fore and aft ends of the saddle 8. Hence the ends of the valve chest 6 project (like those of the cylinder 5) somewhat beyond the saddle ends 12, 12. Cylinder 5 and valve chest 6 are provided with the usual liners 13 and 14, the latter separated in the middle, and each having an annular series of port openings 15 with intervening bridges to carry the packings of the associated piston valve (not shown) across the openings. Besides the cylinder and valve chest walls and the vertical transverse webs 11, 11 and 12 already mentioned, each saddle half 8 comprises various vertical and horizontal fore and aft webs and flanges 16, 17 and transverse webs and flanges 18, etc., all united and interconnected in the one casting as usual. The particular structure here shown being intended for equipment with piston valves (as already intimated), the valve chest 6 is provided with a flanged lateral connection 19 at its middle for a pipe to supply live steam between the valve heads, etc., as usual.

As shown, each saddle half 8 has the usual integral cylindrically curved saddle web and flanges 20, to seat the locomotive smoke box (not shown) and afford means for securing it. In the midst of the combined structure 20, 20 are a pair of contiguous oblong flange-lipped exhaust openings 22, 22, one in each saddle half 8, for delivering the exhaust steam from the corresponding cylinders 5, 5 to the superjacent exhaust nozzle (not shown) in the locomotive smoke box (not shown). Integral with each saddle structure half 8 are exhaust passages or conduits 24, 24, united at the corresponding discharge opening 22, but branching a little below it and thence extending fore and aft (and a little to one side) to corresponding exhaust-receiving openings 25, 25 in the saddle ends 12, 12. The passages 24, 24 combine the exhaust from the two ends of the corresponding cylinder 5 and transmit the same

to the exhaust nozzle, as will be readily understood.

Instead of being led off from the valve chest 6 through passages within the saddle structure 8, as heretofore, the exhaust is conveyed from the valve chest to the passages 24, 24 at the outside of the saddle ends 12, 12. As here shown, the steam is so conveyed by means of separate conduit structures secured and connected between the valve chest 6 and the saddle openings 25, 25. In the present instance, each of these conduit structures is itself made in two parts: a deep, externally flanged head 27 or 28, fitting and secured to the open end of the valve chest 6 over its liner 14, and provided with an oval flanged lateral outlet neck 29; and a flanged elbow 30 or 31, similarly oval at one end for connection to the neck 29, and gradually curving and changing in cross section to correspond to the less flat oval of the passages 24, 24. As shown, the front valve chest head 27 has an opening with a removable cover 32 (aligned 10 and corresponding with the bore of the valve chest 6) to permit removal of the valve (not shown), upon occasion, without disturbance of the connections; and this cover has a curved inner wall 33 opposite the lateral neck 29 for directing the flow of exhaust steam to the latter smoothly and without eddies. This head 32 may also be provided with a lateral neck connection 34 for supplying an exhaust steam feed water heater (not shown). The rear valve chest head 28 has a similarly curved wall 35, and carries the usual rearward extending valve stem cross head guide structure 36, as well as the gland box 37 for the valve stem packing (not shown). One of the rear elbows 31 is provided with a flanged neck connection 38 for admitting exhaust steam from the locomotive booster engine (or other auxiliaries) to the corresponding saddle passage 24 along with that from the rear end of the corresponding main cylinder 5.

If, now, the course of the exhaust steam is traced on Figs. 1, 2 and 3 from either end of each main valve chest 6 to the exhaust nozzle opening 22 in the top of the saddle 8, it will be seen that the passage 27, 30 (or 28, 31), 24 is everywhere of ample area, free and unrestricted, of well-rounded shape (except at the rectangular delivery opening 55 22), with a minimum number of curves or bends, all easy and well rounded. The steam taken by the conduit structures is led off endwise from the valve chest 6 instead of laterally, so that the most ample 60 area of passage for it is provided without such abrupt changes in direction and narrow passages as would be entailed by a lateral connection similar to that at 7, 17.

We make no claim herein to the valve 35 stem guide, the same being made the sub-

ject matter of divisional application, Serial No. 16265, filed March 18th, 1925.

What we claim is:

1. A locomotive saddle structure comprising a main valve chest and openings in the saddle for receiving the exhaust steam, with means outside of the saddle ends to front and rear, for conveying the exhaust from the ends of said valve chest to said saddle 75 passages.

2. A locomotive saddle structure comprising a main valve chest with open ended bore for a piston valve, and openings in the saddle for receiving the exhaust steam; together with separate exhaust conduit structures secured over the ends of said bore and connected to said saddle openings.

3. A locomotive saddle structure comprising a main valve chest with open ends projecting beyond the saddle ends and saddle 85 openings for receiving the exhaust steam, with means for taking the exhaust steam from said open valve chest ends and conveying the same to said saddle openings.

4. A one-piece locomotive saddle structure comprising a main valve chest and openings in the saddle for receiving the exhaust steam, together with separate exhaust conduit means secured and connected between said valve chest and said saddle 90 exhaust openings.

5. A locomotive cylinder and saddle construction comprising, as one part, a cylinder and a valve chest with their interconnecting ports, and saddle passages for combining the exhaust from the two cylinder ends and transmitting the same to the exhaust nozzle; together with separate exhaust conduit means secured and connected between said valve chest and said saddle 100 exhaust passages.

6. A locomotive cylinder and saddle construction comprising, as one part, a cylinder and a valve chest with their interconnecting ports, and saddle passages for combining the exhaust from the two cylinder ends and transmitting the same to the exhaust nozzle; together with separate exhaust conduit structures secured over the ends of said valve chest and connected to said saddle 110 exhaust passages.

7. A locomotive saddle structure having passages for combining the exhaust steam from the main cylinder ends, with means for conveying the exhaust to said passages 120 having a connection for admitting exhaust steam from other cylinders into the saddle along with that from the main cylinder.

8. A one-piece locomotive cylinder and saddle structure comprising a main valve 125 chest and exhaust-receiving openings in the saddle ends for connection to said valve chest by separate conduit means.

9. A locomotive cylinder and saddle structure comprising a cylinder and a valve chest 130

with their interconnecting ports, and saddle passages for combining the exhaust from the two cylinder ends opening at the ends of the saddle, for connection to said valve chest by separate conduit means.

10. A locomotive cylinder and saddle structure comprising a cylinder and an open ended valve chest with their interconnecting ports, and saddle passages for combin-

ing the exhaust from the two cylinder ends 10 opening at the ends of the saddle, for connection to the open ends of said valve chest by separate conduit means.

In testimony whereof, we have hereunto signed our names.

HERBERT W. SNYDER.
ALBERT J. TOWNSEND.
